UNITED STATES PATENT OFFICE.

MATTHEW H. LOUGHRISE, OF NEW YORK, N. Y.

PROTECTING DEVICE FOR ELECTRIC CONDUCTORS.

1,172,147.

Specification of Letters Patent. Patented Feb. 15, 1916.

Application filed August 18, 1911. Serial No. 644,846.

To all whom it may concern:

Be it known that I, MATTHEW HARKNESS LOUGHRISE, a citizen of the United States, and a resident of the city of New York, borough of Manhattan, in the county and State of New York, have invented a new and Improved Protecting Device for Electric Conductors, of which the following is a full, clear, and exact description.

10 My invention relates to protecting devices for conductors, and particularly the ends of conductors which are led under ground; and the object thereof is to provide a device of the kind described which will form an efficient shield for the end of the said conductor at the point where it emerges from the ground, and prevent the same from being injured, and guard against the admission of water to the conduit or other covering of insulation in which the conductor itself is located.

Reference is to be had to the accompanying drawings forming a part of this specification, in which the same characters of reference indicate the same parts in all the views.

Figure 1 is a view showing the manner in which my protecting device is applied to the end of a conductor at the point where it leaves the ground, part of the construction being shown in section and part in elevation; Fig. 2 is a vertical sectional view on an enlarged scale, showing the entire interior construction of the top of my protecting device; Fig. 3 is a top plan; Fig. 4 is a side elevation of the top of my improved protecting device; and Fig. 5 is a top plan of a modification, showing another form in which the top of my protector can be secured in place.

40 My invention comprises an envelop of porcelain or concrete, indicated at 1, which is shaped like the frustum of a pyramid, and is provided with a tapered hollow bore 45 to give passage to a covering or conduit 5 containing a conductor 4. This conduit is not supported rigidly within the bore of the envelop 1, but is loosely secured therein and is therefore free to expand or vibrate, according to the influence of changes in temperature and the movements of the ground. The bore has its largest diameter at its lower end, so that any movement of the envelop against the conduit 5 will act at the upper end of the conduit, where the conduit is free to move, in preference to where it

is held rigid in coming out of the ground. A clear air space is provided through the bore between the conduit or covering 5 and the envelop, so that shocks or blows will be absorbed by the protecting envelop and will not be transmitted to the covering 5.

2 represents a cap which is preferably made of metal and is shaped so as to be hollow, so that, when the cover is placed on the top of the envelop 1, it will allow the conduit 5 and the conductor 4 inside of the same to pass into the cap a considerable distance before the conductor 4 is led to the outside of the cap. This cap has a flange 2^a which rests upon the top of the envelop 1, and which also has a recess 3 in its edge, through which the conductor 4 passes. The flange 2^a is recessed to permit the passage of a number of studs 7^a, 7^b and 7^c, which are embedded in the envelop 1, and these studs are perforated at their upper ends to give passage to a loop of wire 8, the ends of which are twisted together, as shown in Figs. 3 and 4. This wire 8 will engage the top surface of the flange 2^a and hold the cover or cap against displacement. The conductor 4 will of course have a covering of insulation, and a boss or projection shown at 3' may be formed on the side of the cap 2, this boss being hollow to permit a more convenient formation of the recess 3, into which the insulated conductor 4 fits when the cap and the conductor are in place.

In Figs. 5, 7^a and 7^b are studs, and the flange 2^a of the cap has a pair of lugs spaced apart to receive the stud 7^a between them. These lugs are perforated and through them is passed a pivot pin 12^a, which also enters the aperture in the outer end of the stud 7^a. Through the other stud is passed a pin 12^b, which holds the cap 2 down; and whenever the pin 12^b is removed, the cover can be revolved about the pin 12^a as a hinge. This form shows two conductors 4 and 4^a passing out through recesses 3 and 3^a formed in bosses 3' and 3'^a. The construction is the same otherwise as in the form shown in the first sheet of drawings, except for the different manner of securing the cap in place, as noted.

From the interior construction of my protecting device, as illustrated in Fig. 2, it will be seen that the conduit rises above the top of the envelop 1, and that the conductor is bent out over the upper edge of the conduit 5, and then down to pass out through

the side of the protecting device, at the level of the lower edge of the cap 2. As a result, water entering the protecting device at the joint between the envelop and the cap does not get into the conduit 5, but instead flows into the open space between the conduit and the cap. Hence, any danger of the cable being damaged or otherwise interfered with in its operation by moisture is reduced to a minimum. The construction of the form shown on Fig. 5 is similar. The envelop surrounding the conduit is buried in the earth so as to be of sufficient stability to resist shocks from the outside. My improved protecting device is intended particularly for those types of conduits which are mechanically weak or are in exposed places, such as on railroad tracks, and I have illustrated such a track at 10 on Fig. 1, and shown the conductor 4 connected thereto, this track being an ordinary third rail, such as is commonly used on surface electric railway systems. It is obvious, however, that I may use it in any relation involving a conductor inclosed in a covering or conduit which is buried under the ground and caused to emerge through the surface of the ground at any given point, and I may employ either iron or concrete for the envelop 1, as conditions may dictate.

From the above description it will be apparent that I have devised a new and useful protecting device for electric conductors of superior practical advantage and superior simplicity in construction, and I wish to have it understood that I do not care to be limited to the details shown and described, except in so far as the same are made material by the terms of the claims appended thereto.

Having thus described my invention, I claim as new and desire to secure by Letters Patent:

1. A protecting device for electric conductors, comprising an envelop having an open-ended bore therethrough; a conduit; a hollow cap covering one end of said envelop, said cap having a supporting flange provided with a plurality of recesses and having a lateral passage for said conductor; perforated studs passing through said recesses and embedded in said envelop; and means engaging said studs to retain said cap in place.

2. A protecting device for electric conduits, comprising an envelop embedded in a supporting medium and having a bore therethrough to receive said conduit; a hollow cap for the outer end of said envelop, said cap having a supporting flange provided with recesses; means rigid in said envelop and engaging said recesses; and locking means engaging said last-mentioned means

and said flange to retain the cap in position on said envelop.

65

3. A device as characterized, comprising a weighted envelop having a frusto-conical formed body of solid masonry, said body having an axially-disposed, tapered passage, the wall of said body being increased in thickness toward the lower end thereof for lowering the center of gravity in said body; a tubular conduit having a vertical cylindrical extension loosely fitting in said tapered passage and supported independently of said frusto-conical body; and a removable cover for said conduit.

4. A protecting device for electric conductors comprising an envelop having an open-ended bore therethrough; a vertical tubular conduit extending through said bore and of smaller diameter, the envelop and conduit being independently supported and movable relatively one to the other, electrical conductors loosely placed within said conduit; and a hollow cap supported by said envelop and covering the exposed opening of said bore and the end of said conduit.

5. A protecting device for the outlets of a system of underground tubular conduits, comprising a weighted envelop supported independently of the conduit and having a frusto-conical body with the greater weight in the lower end, said body having a bore therethrough to receive the ends of said conduit, said bore being of larger diameter than said conduit and the exposed end of said conduit being protected with a removable cap.

6. A protecting device for the outlets of a system of underground tubular conduits comprising a frusto-conical envelop with solid walls and the bulk of its weight in the lower end partially embedded in the ground and having a limited free movement on its base, said body being supported independently of the conduit and having a bore therethrough to receive the end of said conduit, said bore being of larger diameter than said conduit and the exposed end of said conduit being protected with a removable cap.

7. The combination of an outer protecting device of a frusto-conical design resting on its base in the ground and having a bore therethrough; an inner tubular protecting conduit, said conduit extending through but of smaller diameter than said bore; the device and conduit being independently supported; electric conductors loosely placed within said conduit; and a hollow cap supported by said outer device and said conduit terminating within said cap.
